(57) **CLAIM**

The ornamental design for a buttress assembly for a surgical stapler, as shown and described.

DESCRIPTION

FIG. 1 is a top perspective view of a buttress assembly for a surgical stapler, showing our new design;

FIG. 2 is a top plan view of the buttress assembly for a surgical stapler of FIG. 1, the opposite bottom plan view being a mirror image thereof;

FIG. 3 is a side elevational view of the buttress assembly for a surgical stapler of FIG. 1;

FIG. 4 is a side elevational view of the buttress assembly for a surgical stapler of FIG. 1, the side elevation view of FIG. 4 being opposite to the side elevation view of FIG. 3;

FIG. 5 is an enlarged front elevational view of the buttress assembly for a surgical stapler of FIG. 1;

FIG. 6 is an enlarged rear elevational view of the buttress assembly for a surgical stapler of FIG. 1;

FIG. 7 is a cross-sectional view of the buttress assembly for a surgical stapler of FIG. 1, taken along line 7-7 of FIG. 1;

FIG. 8 is a cross-sectional view of the buttress assembly for a surgical stapler of FIG. 1, taken along line 8-8 of FIG. 1;

FIG. 9 is a cross-sectional view of the buttress assembly for a surgical stapler of FIG. 1, taken along line 9-9 of FIG. 1;

FIG. 10 is an enlarged cross-sectional view of the buttress assembly for a surgical stapler of FIG. 1, taken along line 10-10 of FIG. 3;

FIG. 11 is an enlarged cross-sectional view of the buttress assembly for a surgical stapler of FIG. 1, taken along line 11-11 of FIG. 3; and,

FIG. 12 is an enlarged cross-sectional view of the buttress assembly for a surgical stapler of FIG. 1, taken along line 12-12 of FIG. 3.
